(57)

CLAIM

The ornamental design for a water bottle nozzle lid, as shown and described.

DESCRIPTION

FIG. 1 is a top perspective view of a water bottle nozzle lid, showing my new design, showing the nozzle in a closed position of use;

FIG. 2 is a front view thereof;

FIG. 3 is a side view thereof;

FIG. 4 is another side view thereof, showing the nozzle in an open position of use;

FIG. 5 is a top plan view thereof, showing the nozzle in a closed position of use; and,

FIG. 6 is a top perspective view thereof, showing the nozzle in an open position of use.

The broken lines in the drawings depict portions of the article that form no part of the claimed design.
